UNITED STATES PATENT OFFICE.

LEOPOLD RAUH, OF DAYTON, OHIO, ASSIGNOR TO THE EGGER REGISTER COMPANY, OF DAYTON, OHIO, A CORPORATION OF OHIO.

MANIFOLD ATTACHMENT FOR TYPE-WRITERS.

1,214,824.

Specification of Letters Patent.

Patented Feb. 6, 1917.

Application filed October 27, 1913, Serial No. 797,386. Renewed December 23, 1916. Serial No. 138,620.

To all whom it may concern:

Be it known that I, LEOPOLD RAUH, a citizen of the United States, and a resident of the city of Dayton, in the county of Montgomery and State of Ohio, have invented certain new and useful Improvements in Manifold Attachments for Type-Writers, of which the following is a full, clear, and exact description, reference being had to the accompanying drawings, forming part of this specification.

My invention relates to attachments for typewriting machines designed to hold and supply the paper for the type printing mechanism in continuous rolls, and in which provision is made for making manifold copies by means of supplemental inking ribbons.

The invention also relates to an attachment for typewriting machines that furnishes means wherewith a plurality of copies may be produced at one and the same type key operation of the typewriting machine.

The object of my invention is to provide a manifolding attachment which can be quickly and easily connected with and disconnected from the typewriting machines, of the visible writing class, so to construct and support said manifolding attachment that the manifolding ribbon and the parts immediately coöperating therewith can be moved into inoperative positions to permit the typewriter to be used in the usual manner without interference between the same and said manifolding attachment.

I propose to apply my invention principally to machines of the type wherein the supply stationery for producing the various copies is wound on rolls, which enables an automatic feed of its web around the platen of the writing machine; however, I lay no claim to the means shown for mounting such stationery supply for use. I, however, provide in my attachment a horizontally fixed knife edge bar for the purpose of cutting the written members into sheets of any desired length.

I provide a construction wherewith by the aid of a single web of ink ribbon and a pair of ribbon spools upon which the same is mounted together with a number of mechanical embodiments coöperating therewith is provided a labor saving device that will benefit the business world.

The methods now generally adopted provide means to guide the ink ribbons to a horizontal position so that the type keys of the writing machine may contact therewith. If the contact is irregular and the layers of ribbon stretches do not perfectly aline or sag away one from another, it will be readily observed that it will not be possible to produce accurate multiples of copies of writing with the aid of such multiple ink ribbons. Further, in cases where the ink ribbons or carbon fabrics lay dormant and nonshifting with the carriage of the writing machine in and between the stationery supply, the uniform impression gained from the ribbon would be lost. I, however, provide, as shown in my drawings and specification, means so that the multiple folds of ink ribbon pass perfectly alined to and fro at all times, maintaining a free ribbon shift, producing, therefore, continuous inking renewal and the possibility for producing legible copies of writings.

The several features of my invention and the various advantages not already elaborated upon and resulting from their use conjointly or otherwise, will be apparent from the following description and claims.

In the drawings, Figure 1 is a side elevation of a typewriting machine, with my improvements applied thereto. Fig. 2 is a top plan view of a portion of the typewriter. Fig. 3 is a side elevation of the attachment for holding and feeding the ink ribbon. Fig. 4 is a plan view of the same. Fig. 5 is a transverse section of the attachment looking toward the left. Fig. 6 is a detailed plan view of one of the shields and tracks for the ink ribbon. Fig. 7 is a similar view, showing the method of mounting the ink ribbon. Fig. 8 is a detail showing the construction for pivoting the attachment to the typewriter frame. Fig. 9 is a rear elevation of the typewriter, with the attachment applied. Fig. 10 is a side elevation of the opposite end of the attachment from that shown in Fig. 3. Fig. 11 is a detail front elevation showing a modified method of mounting the ribbon spool. Fig. 12 is a detail longitudinal section of the ratchet construction for driving the ribbon spools. Fig. 13 is an elevational view of one of the bearing plates, part being broken away.

My improvements may be applied to any

of the well known constructions of typewriting machines for visible writing, but the particular construction of typewriter with which I have chosen to illustrate my improvements is the typewriter known as the Underwood, in which the framework of the machine is indicated by 1, the keys by 2, with the impression cylinder or platen 3 mounted in a carriage 4, which is arranged to be shifted by the operation of the space key to carry the paper from side to side as the writing progresses. In this form of machine, the inking ribbon 5 is mounted on two horizontally disposed spools, one of which is shown at 6 in Fig. 2, which spools are suitably journaled one on one side and the other on the other side of the central portion of the machine, with the ink ribbon carried in front of the impression cylinder or platen, and between which and the ribbon the paper to be written on is passed to receive the impression from the type selected by the keys operated. For the purpose of advancing the paper for the spacing, the impression cylinder or platen over which the paper is carried, is rotated by means of the line space lever 7, pivoted at one side of the carriage frame.

My improved attachment for such a typewriter consists of devices for supporting the supplemental inking ribbon from which the manifold copies are printed, and of the devices for feeding this ribbon from side to side to present continuously a fresh portion thereof to the type during the operation of the machine.

The construction for holding the rolls of paper is particularly illustrated in Figs. 1 and 9, in which a metal frame work is provided, comprising vertical side standards 8, 9, with cross bars 10 at the top and at the bottom 12. This construction as hereinafter detailed comprises no part of my invention.

The lower portion of the frame is supported in such a manner as to hold the same against movement toward or away from the typewriter, but to permit the frame to move freely in the direction of movement of the paper carriage of the typewriter. This may be accomplished in various manners, and, in the present instance, I have shown the bottom 12 as provided with journal bearings for the spindles of a pair of grooved carrying wheels 13, 14, by means of which the frame is supported on the track 15 to be carried from side to side, with the reciprocal movement of the carriage of the typewriter, and to which the frame is secured as will be hereinafter described.

At suitable points on the uprights 8, 9, of the roll paper frame, angle plates 15, 16, are secured, supported so that the rolls of paper 19, 20, 21 and 22 can be readily and easily mounted in the frame to rotate freely as the several webs of paper are drawn from

the rolls. On the end of the paper rolls in which the spindles are supported in the plate 16, the rolls are preferably provided with disk washers 23, to prevent the paper from coming in contact with the standard, while on the opposite end the disks are omitted, and a tension device 25, 26, is provided to bear against the end of each roll of paper to maintain the proper tension on the paper.

The track 15 upon which the paper roll frame rides is properly supported at the bottom and rear of the typewriter frame by the brackets 29, which brackets are supported and rigidly secured to the main framework at 30, 30, by screws or otherwise; while the roll paper frame is held in vertical position to be moved from side to side with the movement of the typewriter carriage by arms 31, 31, which are pivotally secured to the carriage attachment and at the outer ends are hooked over studs on the roll paper frame at 32, 32.

From the foregoing description, it will be evident that the type of paper rolls and supports, arbitrarily chosen to be illustrated here, is such that the roll paper frame may be readily and easily secured to the typewriting machine without interfering with or altering the machine structure in any way, and also that it is independent of the manifolding to be now described.

The manifolding device proper comprises a supplemental or manifolding ribbon which is supported upon a frame mounted on and movable with the paper carriage of the typewriter. This frame also carries novelly shaped punched shields about which the inked ribbon is drawn to cause a plurality of folds thereof to extend parallel with the platen and between the same and the type carrying member at the point of contact of the type with the platen. This frame is preferably pivotally mounted on the paper carriage to permit the ribbon tracks and the ribbon to be moved upwardly and rearwardly to carry the ribbon into an inoperative position, thereby permitting the typewriter to be used in the ordinary manner without any interference with the manifolding attachment. Further, by moving the several folds of the manifolding ribbon into this elevated or inoperative position, it is much easier to thread the several webs of paper between the various folds of the ribbon.

I will now proceed to describe the form of mechanism by means of which the invention may preferably be attached to a typewriter of the character above described.

The frame for holding and shifting the supplemental inking ribbon for the manifold copies comprises vertical end plates 33, 34, with a guide plate 35 for the paper extending between the plates, and with a bar 36 in front of the guide plate, which bar

serves as a cutting edge for serving the webs of paper from the roll after they are written upon, in such lengths as desired.

The framework is pivotally mounted in bearing plates 37, 38, which are secured on the end bars 39, 40, of the typewriter carriage.

On one end plate of the frame 33, a pivot stud 41 has its bearing in the plate 37, while at the opposite end (Figs. 8 and 13) the stud 42 fits within a socket 43 in the pin 44 pivotally mounted in the bearing plate 38. This pin 44 is spring-pressed by the coiled spring 45 and is provided with the head 46 for rotating the pin 44, and a stud 47 on the pin bears on a cam slot 48 on the bearing, so that by rotating the pin 44 the stud 42 will be released to permit removal of the entire frame.

The supplemental or manifolding ink ribbon is carried on ribbon spools 51, 52, which are loosely mounted on spool shafts 49, 50, supported in the end plates 33, 34, of the frame, and means are provided for locking either one of the spools to its respective shaft,

25 while the other spool remains loose so that both shafts may be driven simultaneously in the same direction, and the tight spool will alone take up the ribbon. Each spool shaft is provided with a head 101 to bear against the side face of its spool, and is formed with a screwthreaded opposite end to receive the lock nut 53, 54, and with a right and left thread for the respective shafts. Mounted loosely on each shaft is a sleeve 102, upon

30 which the ratchets 55, 56, are respectively secured, and the sleeves and spools are tightened on their respective shafts by tightening the lock nut. Each ratchet is engaged by a pawl 57, 58, mounted on a pawl carrier 59,

40 60. Each pawl carrier is connected by a connecting bar 61, 62, with an arm 63, 64, on a common rock shaft 65, which extends between the end walls of the frame, so that by rocking the shaft 65 both ratchets are

45 actuated in the same direction. One of the lock nuts 53 or 54 is loosened and the other tightened, and it will be evident that one of the ribbon spools will be actuated to wind the ribbon extending between them, while the 50 ribbon is drawn off from the other spool which is free from the shaft.

To reverse the movement of the ribbon, the tight nut is loosened and the loose nut tightened, and the same movement of the 55 common rock shaft will actuate the other ribbon spool to take up the ribbon.

The rock shaft is actuated by an extension 66 of the arm 63, to which is pivoted the bar 67, the bent outer end of which lies in the 60 pathway of an arm 68 (Fig. 2) on the line space lever 7, so that with each operation of the line space lever, the ribbon spools are shifted to present a fresh portion of the ribbon to the type.

65 By providing loosely mounted sleeves for

the driving ratchets and clamping both the ratchets and spools to their respective shafts by the lock nut, I can arrange the threaded end of the spool shafts either inside the frame as shown in Fig. 2, or outside as shown in Fig. 11.

In order that the ribbon 69 extending between the spools 51, 52 may be utilized for making a plurality of duplicated copies at the same time that the main ribbon 5 is used for the original impression, I employ a pair of frames 70, 71, depending from the end walls 33, 34 of the attachment. The frame 70 is provided with a partially right triangular shield 72, around the diagonal edge 80 of which the ribbon is carried and turned at right angles parallel to the main ribbon in front of the impression cylinder, and thence to the shield 71 upwardly through the slot 73, thence over and around the projecting arm 74 and back underneath the shield 70, around the arm 75 and back between the two folds of ribbon, around the diagonal edge 76 of the shield 71 and thence to the spool 52. In this way, three sections 90 of the single ribbon 69 are presented together with the main ribbon in front of the impression cylinder to receive the impression from the type, and provision is thus made for manifold imprints from the type.

It will be noticed that in winding the ribbon around and through the punched shield, the sections of the ribbons from end to end are all in close contact, and even at the ends of the lines of printing a clear impression 100 can be made from the type. Inasmuch as the supplemental ribbon is mounted on the reciprocating carriage, while the main ribbon is mounted on the fixed frame of the typewriter in which frame the type bars are 105 mounted, the supplemental ribbon must lie in close contact with the impression cylinder throughout its length. If at the ends the thickness of the shields intervened between the inking ribbon and the cylinder, the type 110 impressions might be blurred or skipped.

As already stated, the cross bar 36 provides the cutting edge for severing the paper from the roll, and in order that the paper strips may be held tightly against the knife bar when being torn off, I provide a bar 78 (Fig. 5) to co-operate with the cutter. This bar is mounted in arms 79 pivoted at 81 to the end plates 33, 34 of the attachment, and the bar is normally held away from the cutter bar by the springs 80 attached between the arms and the end plates. At one end an extension arm 82 is provided for the bar 78, by means of which the bar may be brought into contact with the cutter to hold 120 the paper passing between the two bars.

In order to hold the attachment rigid in position, a pair of cam plates 83, 83 (Fig. 4) are provided, one for each end 33, 34 of the frame, which are arranged to seat over 125

the ends 39, 40 of the typewriter carriage, and in order to raise the attachment for the convenient threading of the paper, I provide a finger pull 84.

5 To provide proper tension for the supplemental ribbon spools 51, 52, each is provided with a roller 85 bearing on the periphery of one of the spool disks. Each roller is mounted in an arm 86, pivoted at 10 87 to its respective end plate 33, 34, and the tension is adjusted by a coiled spring 88 attached to the end wall and to a rod 89 adjustably mounted on the arm 86 and adjusted by the thumb nut 90.

15 If roll paper stationery is used to load the machine, as is preferred and has been described, the paper rolls are first mounted in the roll frame as heretofore described, and the paper webs 91, 92, 93 and 94 are 20 passed over the guide rods 95, which are mounted on standards 96 on the arms 31 which brace the roll frame in position. The paper webs are then passed under and partially around the impression roller, the web 25 91 in contact with this roller, with the strips of inking ribbon interposed between the sheets. In order to accomplish this conveniently, the ribbon attachment is first raised by the finger pull 84, and then the 30 attachment is lowered with the sections of the supplemental ribbon and the paper webs between the main typewriter ribbon and the impression roller. The webs of paper are then passed up between the cutting knife 35 and the coöperating bar 78, and the paper strips are torn off evenly and the machine is ready for use.

The paper web 94 receives the first impression from the type, inked by the main 40 typewriter inking ribbon, and the other webs 93, 92 and 91, in the order named, receive their impressions from the respective sections of the supplemental inking ribbon. The rolls of paper and the webs therefrom 45 shift in the ordinary way for the letter spacing and the operation of the line space lever rotates the impression roller to feed the paper for the next line.

With the operation of the line space lever, 50 the supplemental ribbon spools are also actuated as heretofore described to shift the supplemental ribbon. As the paper is fed by the impression roller, it is carried up over the guide plate 35, and when a sufficient length of the web has been written on, 55 the sheet may be torn off on the cutting edge.

It will be convenient to have the uppermost sheet which takes the original impression from the main ribbon, printed so as to 60 indicate when the proper length of sheet has been reached.

While I have illustrated the method of 65 extending the folds of the supplemental inking ribbon, so as to provide for three ribbon strips for ink copies, it will be evident

that the ribbon can be extended in and around the shield tracks so as to make five copies, or even a greater number, with a single inking ribbon.

With the folds of the ribbon as shown, 70 the proper tension can be maintained on the ribbon, and it can be readily drawn from one receiving spool to the other. By supplying rollers over which the ribbon can be drawn from one arm of the guide plate to 75 the other, many more folds of the ribbon can be built up without the ribbon binding in its track.

The operation of the device will be readily understood from the foregoing description 80 of the several parts thereof, and it will be apparent that I have provided a manifolding device which can be very quickly and very easily attached to and removed from typewriting machines now on the market 85 with little or no modification or alteration of said machine. The device may be connected with many of the machines without any change whatever either in the machine or in the device. In the case of some machines, however, it may be necessary to make slight alterations to connect the device to the different sizes and shapes of the typewriter frames. By making the spindles of the supplemental ribbon spools reversible 95 it is possible to adapt the device to machines, the frames of which are of materially different widths, with no change other than moving the ribbon spool lock nuts from the inside to the outside of the supporting frame 100 or vice versa. It will also be apparent that while we have shown this manifolding device in the form of an attachment, it can readily be built into the machine and made a part thereof at the factory. Further, it 105 will be apparent that the manifolding devices are so mounted that they can be moved away from the writing devices of the machine to permit these devices to be operated in the usual manner, and when so operated, 110 the manifolding devices will in no wise interfere with the operation of the typewriter as such.

It will be apparent that I have provided means whereby a plurality of copies may be 115 simultaneously produced from a single inking ribbon, this ribbon being supported in such a manner as to cause a plurality of folds thereof to extend between the platen and the type at the point of printing.

It will be understood that while I have shown and described the invention as applied to typewriting machines, many features thereof can be adapted to machines of a widely different character. For example, 125 the use of a single inking ribbon to simultaneously produce a plurality of copies is by no means limited to writing machines, but could be readily applied to devices of various kinds where manifold copies are de- 130

sired. It will also be understood that while I have shown and described one form of the invention, this form is chosen for the purpose of illustration only and I do not wish to be limited to the details of construction shown and described, for obvious modifications will occur to a person skilled in the art.

Having thus described my invention, what I claim as new and desire to secure by Letters Patent, is:—

1. A manifolding device for typewriters comprising a pair of ribbon spools, carried by the carriage of the typewriter, a single continuous web of ribbon thereon, means for automatically actuating the spools for feeding the ribbon from one to the other, and ribbon guides mounted on the carriage for supporting a plurality of folds of said ribbon, said guides having inclosed apertures therein for each fold, and one of said guides having an inclosed slot and a diagonal edge adjacent said slot to permit the ribbon to

be doubled on itself, and then passed between the two folds thereof.

2. A manifolding device for typewriters comprising a pair of ribbon spools, carried by the carriage of the typewriter, a single continuous web of ribbon thereon, means for automatically actuating the spools for feeding the ribbon from one to the other, and ribbon guides mounted on the carriage for supporting a plurality of folds of said ribbon, said guides comprising plates having projecting arms inclosing triangular openings for directing and receiving the ribbon from the spools, and an inclosed slot adjacent the diagonal edge of the opening in one of the guides for holding and guarding the intermediate folds.
